US00D810782S

(12) **United States Design Patent** (10) Patent No.: **US D810,782 S**
(45) Date of Patent: **** Feb. 20, 2018**

(54) **CELLULAR PHONE WITH GRAPHICAL
USER INTERFACE**

(71) Applicant: **LG ELECTRONICS INC.**, Seoul
(KR)

(72) Inventors: **Jaehyeok Park**, Seoul (KR); **Jisoon Park**, Seoul (KR); **Hana Jeong**, Seoul (KR)

(73) Assignee: **LG ELECTRONICS INC.**, Seoul
(KR)

(**) Term: **15 Years**

(21) Appl. No.: **35/501,325**

(22) Filed: **Feb. 2, 2016**

(80) **Hague Agreement Data**

Int. Filing Date: **Feb. 2, 2016**

Int. Reg. No.: **DM/089535**

Int. Reg. Date: **Feb. 2, 2016**

Int. Reg. Pub. Date: **Aug. 5, 2016**

(30) **Foreign Application Priority Data**

Aug. 5, 2015 (KR) 30-2015-0039666

(51) **LOC (11) Cl.** **14-04**

(52) **U.S. Cl.**

USPC **D14/494**
